UNITED STATES PATENT OFFICE.

LOUIS BINDER, OF NEWARK, NEW JERSEY.

BOX.

1,330,300.

Specification of Letters Patent. Patented Feb. 10, 1920.

Application filed June 27, 1919. Serial No. 307,228.

To all whom it may concern:

Be it known that I, LOUIS BINDER, a citizen of the United States, and a resident of Newark, county of Essex, and State of New Jersey, have invented certain new and useful Improvements in Boxes, of which the following is a specification.

This invention relates to an improved box of the type usually referred to as a paper box, which is usually made from sheets of cardboard, flexible in the sheet but, when folded and assembled, having sufficient stiffness to maintain its shape, and the invention is particularly designed to provide a box of this kind that has a desirable feature in that the top and bottom edges are provided with a cornice or coping effect; in other words, they project beyond the body of the box laterally, and in which the cover is so constructed and affixed that it can be swung back to an open position and it will remain in such open position without straining the cover or the box.

The invention is further designed to provide a box having a cover which is easily closed, but which requires a slight application of force to open by reason of the attachment of the cover and the construction of its free end where it engages the front edge of the box.

The invention is illustrated in the accompanying drawing, in which it is necessary to exaggerate the thickness of the walls relative to the size of the box, and in which there is also an exaggeration of the angular position that the lid assumes relative to the box body when the lid is shut, this exaggeration being necessary to clearly illustrate the invention.

In said drawing, Figure 1 is a front view with the body of the box broken away at one end, this view showing the lid open. Fig. 2 is a vertical cross-section of the box shown in Fig. 1, and Figure 3 is a view similar to Fig. 2, with the bottom portion of the box shown in elevation and with the lid shut.

It will be understood that particular forms of boxes can be employed other than that shown, and that the parts in themselves can be differently formed and assembled than in the manner illustrated, but in the type of box shown the box comprises a front 10, sides 11 and a back 12 formed by folding one strip of cardboard into rectangular shape and suitably securing the

corners, usually by pasting reinforcing strips thereon, which are not shown and which form of structure is old and well known in the box trade.

These sides are usually formed from wings that extend from the bottom 13, and this part of the box so far described I will call the body portion, and it sets into a base comprising a base sheet 14 which extends beyond the edges of the body portion and is again bent inward or upon itself, preferably at an angle, as shown at 15, to form the extending or projecting edges, an inner fold 16, into which the body portion fits, and a securing strip 17, which can be pasted to hold the parts in normal position and also acts as a brace. The body portion and the base are usually pasted where they abut at the bottom so that they are permanently fastened together.

The cover is usually made to match the bottom portion so that the box looks even and symmetrical when it is assembled, and in the form shown the cover is sealed to the base portion, since the top plate 18 has the angular strip 19, the inner fold 20 and the reinforcing or securing strip 21, and to further strengthen the lid I preferably insert a bracing sheet 22. A sheet 23 is placed inside the lid and extends nearly across the lid in the preferred form, leaving the spaces 24 between its side edges and the inner folds 20 at the sides, so that the box can pass over the top edges of the sides 11 of the body portion, the sheet 23 being arranged at its rear edge 25 so that it is substantially pivotal to the top edge of the back 12, to which it is hinged by a suitable hinge, usually in boxes of cardboard by a strip 26 of linen or tough fabric, the end of this hinged strip being secured to the cover also by means of strips 27 of cardboard, which are thick enough to take up the space between the upper part of the cover and the end 25 of the sheet 23, so that the movement backward of the lid is possible by reason of the point at which the swinging takes place, and the rear projecting part 28 of the cover acts as a stop and the lid 105 can be swung backward and remains in such open position since it is beyond the center of the swinging movement and naturally has a tendency to rest against the part 28, which acts as a stop.

The outer or forward end of the sheet 23 is free and spaced apart from the inside of

the cover, and in order to provide this spacing, and also to give the required spring combined with stiffness, the end 29, which is the forward end of the sheet, is bent so 5 as to be spaced from the side top face of the cover and is preferably fastened by pasting or otherwise, as at 30, to prevent movement of the sheet itself. The free end 29 of the sheet and the forward wall 31 of the 10 cover are spaced so that they will receive the top edge 32 of the front wall of the body portion. As stated hereinbefore, the spaces and dimensions of these parts are slightly 15 exaggerated to bring out more clearly the function of this arrangement, and in Fig. 3 the closed lid shows that the free end 29 on the inner side of the cover frictionally engages the front wall of the body portion on the inside, and the front wall 31 of the 20 cover engages the front wall of the body portion on the outside, and the lid does not accidentally come open but is held shut by this frictional engagement.

It will also be noted that the free end 29 25 is below the top edge of the cover and below the axis of the hinge; in other words, below the axis of the point on which the cover swings, so that any movement upward of the cover tends to swing the lid slightly outward on its upward movement as it is traveling through the lower arc of a circle with the hinge of the lid as its center, but this arrangement is permitted through the spring or slight elasticity of the end 29 of the 30 sheet 23, this being usually made of cardboard.

It will be noted in Fig. 3 that the lid is shown at an incline, but this incline is exaggerated, as the box in reality has its lid 40 more nearly level, but in order to emphasize the movement of the free end 29 below the top edge of the body portion, which is usually the level on which the cover swings, the space is enlarged in the drawing so as to make this point clear, although it will be 45 understood that, if desired, the box can be made just as illustrated, with a noticeable inclination of the cover.

It will thus be seen that I have devised 50 a box with an overhanging cover that is durable, the cover and the base portion having stiffened and braced edges, and in which the sides and the front wall of the body portion are seated into the space on three 55 sides of the cover between the outer edges of the sheet 23 and the inner folds 20, this space 24 receiving the top edges of these walls and making a tight closure, which is

desirable when the box is used for holding articles that might be affected if this closure 60 was not tight.

I claim:

1. A box having walls and a cover, the cover having overhanging edges, a hinge securing the cover to the top edge of the rear wall, the cover having a sheet on its inner face and having a downwardly projecting fold to engage the outer side of the front wall, the front edge of the sheet and the fold being spaced to receive the top edge 70 of the front wall, the front edge of the sheet being free so as to have a limited resiliency so that its friction against the front wall increases as it is moved from its closed position toward the top edge of the front wall. 75

2. A box having side walls and having a cover formed of a top having its edges turned inwardly at an angle and then back to the top to form inner folds to fit over the outside of the walls, a hinge securing 80 the cover to the top edge of the rear wall, and a resilient lip spaced from the inside of the top to engage the inner side of the wall below the top edge thereof and below the level of the hinge when the cover is shut. 85

3. A box having side walls and having a cover formed of a top having its edges turned inwardly at an angle and then back to the top to form inner folds to fit over the outside of the walls, a hinge securing 90 the cover to the top edge of the rear wall, and a sheet secured to the inside of the top near the free end thereof and to the cover at the point where it is hinged, the end of the sheet at the free end of the cover being 95 bent so as to be spaced therefrom and form a resilient lip to engage the inner face of the front wall below the level of the hinge when the cover is shut.

4. A box having side walls and having 100 a cover formed of a top having its edges turned inwardly at an angle and then back to the top to form inner folds to fit over the outside of the walls, a hinge securing 105 the cover at the juncture of one of the inner folds with an inwardly turned edge to the top edge of the rear wall of the box, whereby the inwardly turned edge acts as a stop when the lid is opened and thus acts to hold the lid in a rearwardly inclined position on 110 its hinge.

In testimony that I claim the foregoing I have hereto set my hand this 26th day of June, 1919.

LOUIS BINDER.
